(57) **CLAIM**

I claim the ornamental design for a chopstick-type utensil, as shown and described.

DESCRIPTION

FIG. 1 is a perspective view of a chopstick-type utensil, showing my new design;
FIG. 2 is a front elevational view of FIG. 1;
FIG. 3 is a rear elevational view of FIG. 1;
FIG. 4 is a right-side elevational view of FIG. 1, the left-side elevational view being a mirror image thereof;
FIG. 5 is a top plan view of FIG. 1; and,
FIG. 6 is a bottom plan view of FIG. 1.

1 Claim, 3 Drawing Sheets
